UNITED STATES PATENT OFFICE.

EMANUEL AUFIERO, OF BROOKLYN, NEW YORK.

SIGNAL DEVICE.

1,226,624.

Specification of Letters Patent. Patented May 22, 1917.

Application filed October 29, 1913. Serial No. 798,101.

To all whom it may concern:

Be it known that I, EMANUEL AUFIERO, a citizen of the United States, and a resident of Brooklyn, county of Kings, New York, have invented a new and useful Improvement in Signal Devices, which invention is fully set forth in the following specification.

This invention relates particularly to diaphragm-devices where the diaphragm is actuated mechanically by the teeth or cams of a suitable rotary member acting upon a projection carried by the diaphragm, and is particularly adapted for a device located at some distance from the operating-handle which is in convenient reach of the attendant. The main object of the invention is to produce a device of this character which is always ready to give an adequate signal-alarm of the desired loudness and pitch and duration, by means of simple and easy manipulation by the attendant. Other objects are to produce an inexpensive, easily assembled, compact, durable, and ever-ready device of the character indicated. A striking feature of the invention is the employment of two oppositely-working pawl-and-ratchet devices for actuating the rotor in continuous direction, and two drums with oppositely-wound cables for actuating said devices. Other features of the invention will be hereinafter pointed out and claimed.

The invention will be best understood by reference to the annexed drawings, in which Figure 1 shows a preferred embodiment thereof, partly in longitudinal section; and Figs. 2 and 3 are diagrammatic views illustrating modifications.

Referring to Fig. 1, the diaphragm 1 is clamped between the front wall 2 and the flanged rear-casing 3, preferably with washers and screws, as shown. Any suitable form of horn or trumpet may be secured to or made integral with the front casing, and it will be noted that the rear-casing is a seam-less member requiring no separate cap or closure at the rear. The shaft 4 is journaled transversely within the casing, preferably in the adjustable bearings 5—5 that are screw-threaded into the walls of the casing and may be locked in place in any convenient manner. Fast upon this shaft is the comparatively large toothed-wheel or actuating-cam or "rotor" 6 to act upon the projection 7, which extends adjustably from the rear of the diaphragm and projects into the path of the teeth or cams of the rotor. A member 8,

shown as a disk, is also fast on the shaft, and carries two (spring-pressed) pawls, one on each side. On each side of this member 8 there is a comparatively small drum loose upon the shaft and carrying a ratchet to engage one of the pawls aforesaid. One pawl, as 9, lies behind its ratchet 10; while the other pawl 11 lies in front of its ratchet 12. A cable 13 is wound one or more times around the drum of ratchet 10; and a similar cable 14 is wound, in opposite direction, around the drum of ratchet 12. At their inner ends these cables are secured to a spring or springs 15, here shown as a separate helical spring for each cable and secured to a stationary support, as post 16. The outer ends of the cables are shown as united to the cross-head 17, from which extends the pulling-member 18 that passes out through a hole in the rear end of the casing.

As member 18 is drawn outward, these oppositely-wound cables cause their respective drums to rotate in directions opposite to each other; and as member 18 is released, the springs 15, retracting these cables, cause reverse rotation of their respective drums, each in the direction opposite to the other, as before. Consequently, during the positive outward movement caused by the attendant, one pawl and ratchet (9 and 10) will rotate member 8 and rotor 6 (counter-clockwise, as viewed from the top of the sheet), while the other ratchet turns idly under its pawl; and, during the reverse movement due to the spring, the other pawl and ratchet (11 and 12) rotate rotor 7 in the same (counter-clockwise) direction. In short, there are two complete revolutions of the rotor, for each to-and-fro movement of the pulling-member.

Within reach of the attendant is located convenient means for actuating the device, comprising preferably the semi-annual casting 19, in which is journaled the shaft 20 with its crank-handle 21, and with the partial-pulley or quadrant 22 fast on the shaft and of a radius many times greater than that of the two drums; and at the outer corner 23 of this quadrant is secured the pulling-member 18. Preferably this pulling-member consists of a chain, though it may be a cord or cable of any suitable material and construction. Preferably, also, this pulling-member is surrounded by a seamless tubing 24, and the latter is reinforced on the outside, at 25, as by the usual spirally-wound

"flexible-tubing" so-called. One end of this compound sheathing 24-25 is secured to the main casing 2, around the hole for the pulling-member; and the other end to the secondary casing 19, around a similar hole located about opposite the normal position of the attachment-point 23. In a construction of the proportions indicated, a single throw of the handle 21 would suffice to produce a complete revolution of the drums, followed by a complete reverse revolution thereof,—or two complete high-speed revolutions of the rotor for one manipulation of the handle.

If desired, in place of the two separate cables 13 and 14 and the springs 15 (as in Fig. 1), a single cable 26 may be wound around one drum and then, after passing around a pulley 27, wound in the reverse direction around the other drum (as in Figs. 2 and 20 3); and one end of said cable may be attached to a single spring 28 with the other end attached to the operating handle 29 (as in Fig. 2), or the two ends of said cable may be attached to the opposite arms of an operating-lever 30, as in Fig. 3.

The invention has thus been described with considerable detail, but only for the sake of clearness, since the invention may be embodied in various forms, parts may 30 be transposed, and parts of the invention used to the exclusion of other parts.

The invention having thus been fully described, what is claimed is:

1. A signal-alarm device, comprising an acoustic diaphragm, a shaft having fast thereon a toothed-wheel adapted to vibrate said diaphragm, two drums loose on said shaft, alternately-working pawl-and-ratchet devices connecting the respective drums with 35 said shaft, a spring-connected cable wound on each drum with the turns of said windings in opposite directions on the respective

drums, and means within control of the attendant for drawing upon said cable-turns intermittently against the spring-tension, whereby said wheel is rotated continuously to vibrate said diaphragm during both movements of said cable.

2. A signal-alarm device comprising an acoustic diaphragm and a rotor for vibrating the same, two pawl-and-ratchet devices operating alternately to actuate said rotor, and two drums with oppositely-wound cables, said cables being resiliently secured at one end and connected at the other to an actuating-handle. 50 55

3. A signal-alarm device, comprising an acoustic diaphragm and a rotor for vibrating the same, two drums with oppositely-wound cables secured resiliently at one end 60 and connected at the other to an actuating-handle, and rotor-operating mechanism actuated thereby.

4. A signal-alarm device, comprising an acoustic diaphragm and a comparatively 65 large rotor having circumferential teeth for vibrating the same, two pawl-and-ratchet devices alternately actuating said rotor, two comparatively small drums each having a cable oppositely wound thereon for actuating said devices, and a comparatively long lever-handle connected thereto, whereby comparatively short angular travel of the hand 70 while upon said handle produces greater angular travel of said drums and still greater 75 angular travel of said rotor.

In testimony whereof I have signed this specification in the presence of two subscribing witnesses.

EMANUEL AUFIERO.
